Primary Examiner — T Chase Nelson*Assistant Examiner* — Kelly L Gross(74) *Attorney, Agent, or Firm* — Hard IP LLC(57) **CLAIM**

The ornamental design for an orthopedic bunion support, as shown and described.

DESCRIPTION

1. Orthopedic bunion support

FIG. 1.1 is a perspective view of an orthopedic bunion support in accordance with the present design;

FIG. 1.2 is a front view in an alternate configuration;

FIG. 1.3 is a rear view thereof;

FIG. 1.4 is a left view in an alternate configuration;

FIG. 1.5 is a right view thereof;

FIG. 1.6 is a top view in an alternate configuration;

FIG. 1.7 is a bottom view thereof.
